UNITED STATES PATENT OFFICE.

HARUHIKO OZAKI, OF YOKOHAMA, JAPAN.

ELECTRIC INCANDESCENT LAMP.

1,374,766.

Specification of Letters Patent. Patented Apr. 12, 1921,

Application filed October 19, 1918. Serial No. 258,807.

To all whom it may concern:

Be it known that I, HARUHIKO OZAKI, a subject of the Emperor of Japan, and resident of Yokohama, Japan, have invented 5 certain new and useful Improvements in Electric Incandescent Lamps, of which the following is a specification.

This invention relates to electric incandescent lamps and more particularly to the 10 supporting device for carrying the metallic filament.

The object of this invention is to provide an improved device of this character which, by reason of its construction, prevents the 15 breaking of the filament at the point where the same is carried by the support and thus increases the life of the lamp.

The distinguishing features of this invention and its advantages over the ordinary 20 construction will be apparent from the following description in connection with the accompanying drawings, in which like parts in the several views have been given the same reference letters.

25 Fig. 1 is an enlarged view showing the portion of the supporting device constructed according to my invention.

Fig. 2 is a side view, drawn to a smaller scale, showing the anchor inserted into the 30 hub of a stem embodying my invention.

Fig. 3 is a plan view of Fig. 2.

Fig. 4 is a side view, showing a modification of my invention.

Fig. 5 is a plan view of Fig. 4.

35 Fig. 6 is an elevation in perspective showing the complete lamp provided with the supporting device according to my invention.

Referring now to Fig. 1 it will be readily 40 seen how I provide a relatively large curved supporting surface for the hook K^2 , which is formed with a smooth surface at the point A^2 where the filament F is supported and thus I avoid any cutting or abrading action 45 caused by distortion of the material forming the support and also I avoid the sharp bending of the filament F at this point.

In forming the anchor (hook and arm) I 50 select a material which has a highly elasticity, high melting point, low conductivity of heat and is non-volatile, preferably in the form of a flat strip or a ribbon with rectangular cross-section. One end of the strip 55 or the ribbon is, by bending in suitable dies or otherwise, shaped into U-shape to form

the hook, the base of the hook K^2 being curved transversely and formed with a smooth curved surface A^2 on the interior thereof, having its center of curvature outside of the hook, as shown in Fig. 1. In other words, the one end of the support is curved longitudinally and transversely, providing a smooth supporting surface A^2 and having a double curvature on which the filament F is mounted. The other end of the anchor, which is the portion to be inserted 60 into a part of the stem B , is left flat and at about the middle point the arm C is twisted about 90 degrees, as shown in Figs. 2 and 3. Thus these anchors, being fixed in an electric incandescent lamp in the usual manner, provide the necessary flexibility in different 65 directions, due to the flat and twisted construction of the arm, and provide strength sufficient to carry the filament, while the hook part on which the filament is mounted moves with less resistance as a whole, so that any shock from outside the lamp is absorbed or much reduced in transmission to the filament. 70

As a modification of the invention, as shown in Figs. 4 and 5, a circular wire of suitable size and having the same properties mentioned above, may be used to make 85 the anchors instead of the strip or the ribbon. In this case a piece of the wire is first mechanically flattened at one end and then this flattened end is shaped into the U-shaped hook as described above and shown 90 in Fig. 1.

A number of these anchors are inserted in and carried by a central support, which comprises a stem with hub portions B , of insulating material, in the usual manner, as 95 shown in Fig. 6.

I have found that the following materials meet my requirements and are well adapted for forming the anchors above described; molybdenum, tungsten, osmium, platinum, tantalum, steel, nickel, or their alloys and the like. In some cases it may be desirable to use different materials for the anchor and this may be done, for instance, by making the arm portion C (Figs. 2, 3, 4 and 5) of 100 nickel steel and the flat hook A^2 , constructed as described and shown in Fig. 1, of platinum and welded thereto, or the anchor may be of nickel steel with the hook portion plated with platinum. All of these methods 105 and materials have certain advantages in particular cases and are readily adapted to 110

be utilized in the manner described to form a support according to my invention, which has no tendency to cause a breakage of the filament and thus produce a lamp having a maximum length of life.

What I claim is:

1. In an electric incandescent filament lamp, a support for the filament comprising an arm having a flattened end portion formed in a U-shape with the inside lower surface thereof smooth and curved in opposite directions longitudinally and transversely of the axis of the arm, the transverse curvature being formed on a relatively large curve having its center of curvature outside of the support.
2. In an electric incandescent filament lamp, a support for the filament comprising an arm having a flattened end portion formed in a U-shape with the inside lower surface plated with a material adapted to provide a smooth surface and formed with a double curvature in opposite directions

longitudinally and transversely of the axis of the arm.

3. In an electric incandescent filament lamp, a support for the filament comprising an arm having a flattened end portion formed in a U-shape with the inside lower portion thereof of a different material from that of the arm adapted to provide a smooth surface and formed with a double curvature in opposite directions longitudinally and transversely of the axis of the arm.

4. A support for the filament of incandescent lamps comprising an arm having a flattened end portion formed in a U-shape with the inside lower surface thereof covered with platinum to provide a smooth surface and formed with a double curvature in opposite directions longitudinally and transversely of the axis of the arm.

Signed at the city, county and State of New York this 14 day of October, 1918.

HARUHIKO OZAKI.
